WOODBURY STORER HOW, OF CINCINNATI, OHIO.

Letters Patent No. 106,163, dated August 9, 1870.

IMPROVEMENT IN BALANCES.

The Schedule referred to in these Letters Patent and making part of the same.

I, WOODBURY STORER HOW, of Cincinnati, in the county of Hamilton and State of Ohio, have invented a certain Improvement in Balances, of which the following is a specification.

Nature and Objects of the Invention.

My invention belongs to the class of weighing devices, such as steelyards and modifications of the Roman balance or scales, in which a movable counterpoise or poise-weight, or both of these, are substituted for the piece-weights of the pair of scales or equal balance.

My invention relates to the construction of a balance whereby the weight of costly articles, drugs, precious metals, and jewels can be ascertained with the greatest accuracy and minuteness, and the means I employ differ from the common unequal balances in this, that, while in them the article to be weighed is placed at the short arm, and is short in its leverage against a movable counterpoise on the long arm, in my device the article is placed at the remote part of a properly-graduated long arm, and the weight ascertained by a movable poise-weight ranging the long arm toward the fulcrum, the effect of such operation being a virtual substitution for the poise-weight of a load having a long leverage against a common constant counterpoise with a short leverage.

General Description with Reference to the Drawing.

The drawing is a perspective view of one form of my invention, in which is shown an unequal balance, having a long arm, A, and a short arm, A', with the fixed fulcrum B resting on the support C, which is adjusted to and maintained in a vertical position by the set-screw legs J J J, the plumb-bob K, the plumb-line L, and the fixed pin k.

The long arm, A, and its dependencies are counterpoised by the constant counterpoise g, and the adjustable constant counterpoise G, with its screw H.

The vibration of the beam A A' is limited by the arms of the stop M, and the degree of vibration is shown by the index I over the graduated arc N.

The scale-pan D, having its center of gravity below the long arm A, is freely suspended from the knife-edge or pivot E, and the long arm A is marked with counter-numbered equal graduations, b to b', over which the movable poise-weight c ranges toward the fulcrum B.

In the construction of my balance the constant counterpoise or counterpoises may be fixed, or movable, or adjustable on the short arm A', in any form that will serve to counterpoise the long arm A and its dependencies, C D E. The form of unequal balance shown is not preferred, but is convenient.

The whole beam A A' or the long arm, A, may be

made to combine lightness with bulk and rigidity by taking a strip of sheet metal, cut to the right length and about twice the required width, marking it by means of a graduating engine, such as is used in making rules for measurement, stamping the figures so as to be read on both sides of a center line, and then binding or folding the strip lengthwise, so that a cross-section will resemble an inverted U or V.

The graduations b to b' may be in lines with or without notches, in any number or degree of separation, the poise-weight c being subsequently adapted to them, and made either to slide or hang, as may be preferred.

The following are some of the advantages obtained by my invention:

My balance has a preponderating power by the operation of the load upon the long arm, so that a given variation from the true weight being thus rendered more visible, a proportionate accuracy is obtainable.

Another advantage is simplicity of construction in comparison with the common equal balance, which latter is known to require great care and skill in equalizing the parts and in adjusting the fulcrum exactly midway from two pivots for the support of two scale-pans, and similar care and exactness are requisite in various forms of unequal balances, but in making my balance the fulcrum B may at once be fixed near the counterpoise, the pivot E made fast at the end of the graduated long arm A, the scale-pan suspended, and then the poise-weight c be increased or diminished in weight until, from equilibrium at zero, b, it can be moved to the limit of its range, at b', and record the proper number of weights then indicated, as required in D, to restore equilibrium. The intermediate weights and their fractions are included in the one adjustment, and sure to be right if the graduations are equal and the standard weight a true one.

The capacity or weighing power may be increased by counterpoise-weights added to the short arm, either directly upon the arm or suspended from it.

Claim.

I claim as my invention—

The combination of the freely-suspended scale-pan D, the pivot E, the counter-numbered equal graduations b to b', and the movable poise-weight c, with the long arm A of an unequal balance or scales, substantially as and for the purposes hereinbefore set forth.

In testimony of which invention I hereunto set my hand.

WOODBURY STORER HOW.
